UNITED STATES PATENT OFFICE.

SAMUEL J. SHAW, JR., AND PETER G. YOST, OF RIDGEFIELD PARK, NEW JERSEY.

MUSIC-SHEET TURNER.

No. 922,527.

Specification of Letters Patent.

Patented May 25, 1909.

Application filed May 18, 1907. Serial No. 374,434.

To all whom it may concern:

Be it known that we, SAMUEL J. SHAW, Jr., and PETER G. YOST, citizens of the United States, and residents of Ridgefield Park, in the county of Bergen and State of New Jersey, have invented certain new and useful Improvements in Music-Sheet Turners, of which the following is a specification.

This invention relates to music-sheet turners, and its main object is to provide a device of this type by means of which music-sheets may be quickly and easily turned to avoid interruptions in passages of music in changing from one sheet to another.

One of the main features of the invention is an actuator driven by a motor, preferably a spring motor, in such a manner as to have a quick action for turning a sheet whenever the power of the motor is applied to it, and this actuator coöperates with a sheet-holder or series of sheet-holders in such a manner that the sheet-holders are successively and quickly turned from one position to another to bring into view music of successive sheets.

Another important object of our invention is to provide means for returning to a sheet that has been passed, for the purpose of repeating music that has once been played, and in order to accomplish this result we provide in connection with a device used by us for turning music-sheets in the regular manner additional means coöperative therewith for reversing the action of the sheet-turning mechanism.

Other objects and advantages of our invention will appear in the following description and are illustrated in the accompanying drawings, in which—

Figure 1 is a front elevation, broken both horizontally and vertically, illustrating a music-sheet turner embodying our invention. Fig. 2 is a plan of the upper portion of the same, illustrating particularly the sheet-holders and the actuator and the manner in which they coöperate. Fig. 3 is a sectional plan of the lower portion of the apparatus, illustrating the motor for operating the actuator and means for releasing the actuator and reversing the movement thereof. Fig. 4 is a sectional detail of the spring motor for imparting quick movements to the actuator. Figs. 5 and 6 are enlarged details of the clutch hereinafter described, showing the same in central cross-section and in longitudinal section. Figs. 7 and 8 are details

illustrating the fixed and movable clips for holding the sheets of music. Fig. 9 is a vertical section through the lug 15 and the parts thereon. Fig. 10 is a detail view of one of the upper feet.

Similar characters designate like parts in all the figures of the drawings.

In carrying our invention into effect we may make use of any suitable stand or frame for sheet-music and the devices for turning the sheets. This frame may be of the type illustrated, having parallel side-bars 2, an upper horizontal connecting-bar 3, and a lower connecting-bar and shelf 4, all of which parts may be strips of metal or other material plated or ornamented in any desired manner to present a good appearance. In suitable bearings, such as 5 and 6, secured to the horizontal frame members 3 and 4, the vertical shaft 7 may be journaled for rotation. This shaft in our preferred construction constitutes the principal means for transmitting power from a motor to an actuator for turning one or more sheet-holders to bring successive sheets of music into position for the music to be played. The motor employed may be of any suitable type, but we prefer to make use of a small but sufficiently strong spring motor of any suitable type, the power of which may be let off quickly for the purpose of driving the shaft, and which need not be wound up frequently. Such a motor is illustrated in Figs. 1, 3 and 4, and is designated generally by 8. As illustrated, it embodies a casing 9, a large spur-gear 10 for transmitting the power of the spring to the parts to be operated, and suitable parts for winding the spring. In the construction shown the lower main member of the frame of the music-sheet turner has a pair of depending arms 11 and 12 having at their lower ends a rigidly-connected cross-bar 13. The spring motor 8 has an arbor or spindle 14 which at its opposite ends is journaled in the end of the casing 9 and in a lug secured to the lower cross-bar 13.

The spring of the motor 8 is indicated at 16. One end of it is secured in the usual way to the casing 9 and the other end to the spindle 14 which has secured thereto two ratchet-wheels 17 and 18 with which coact spring-pressed pawls 19 and 20. Loose on the spindle 14 is a rotary member 21 one end of which constitutes a spur-pinion 22 of considerable size and the other end of which supports the spring-pressed ratchet 19.

When the pinion 22 is turned by any means in a direction for winding up the spring the movement will be communicated to the ratchet-wheel 17 by the winding-pawl 19 in a manner well understood.

5 The power of the spring 16 may be transmitted in any suitable manner from the motor to the actuator. In this construction the large spur-gear 10 meshes with the large 10 spur-pinion 23 loose on the shaft 7 and connected with the bevel gear 24 normally coupled to the shaft 7 by means of a coupling device 25, thereby assuring the rotation of the shaft 7 in the same direction as the 15 pinion and bevel gear 23 and 24. The means for reversing this movement will be hereafter described.

Between the spur pinion 23 and the lower main member 4 of the frame a rotary dog 26 20 is placed. This dog coöperates with another dog 27 at the end of an escapement lever 28 pivoted on an arm 29 of the frame. This lever 28 is normally held in the position shown in Fig. 1 by means of a spring 30, 25 and is releasable from the dog 26 by the action of the operator for the purpose of permitting movement of said dog.

At the upper end of the device the movement of the main power-transmitting member or shaft 7 is imparted to suitable means 30 for effecting the operation of one or more sheet-holders each adapted to carry a music-sheet. We prefer to make use of a plurality of these sheet-holders in order that a series 35 of music-sheets may be turned quickly one after the other when it becomes necessary to turn the music to a new sheet. In the construction illustrated six such sheet-holders are shown as loosely mounted on a short 40 shaft adjacent to the upper end of the shaft 7 in a bearing at the opposite side of the cross-piece 3 from the bearing 5.

Each sheet-holder in the preferred construction consists of a stiff strip of sheet 45 material such as 31, having at its pivot end a quarter twist which serves the double purpose of reducing the amount of space occupied by the six sheet-holders and also of stiffening each sheet-holder. Each sheet-holder pref- 50 erably carries two clips for sheet-music, one of the clips being illustrated at 32 and consisting of a pair of arms which may be rigid with the sheet-holder 31, while the other clip is movable or adjustable along the sheet- 55 holder for the purpose of engaging music-sheets of different widths and consists of a similar pair of arms projecting from a slide. This movable clip is designated generally by 33. One arm of each clip, whether fixed or 60 movable, is usually made as a separate piece and brazed to the other piece of the clip. Each sheet-holder also embodies an element, preferably in the form of a projection, such for example as the projection 34 from the 65 upper side of the sheet-holder 31, for engage-

ment by the actuator proper employed to turn the sheet-holders and the music-sheets carried thereby. The actuator proper is here shown as a strong pin 35 projecting downwardly from the under side of a slide 36 70 mounted to move with and relatively to a plate, such as 37, secured to the upper end of the same short shaft on which the sheet-holders 31 are loosely supported for rotation. This shaft is designated by 38 and is journaled at its lower end in a bearing 39 similar to that shown at 5. At its upper end this short shaft is threaded and a nut and washer are employed to hold the plate 37 in a fixed position on said short shaft. Below said 75 plate and below the slide 36 said shaft has secured thereto a spur-gear 40 which meshes with a similar spur-gear 41 at the upper end of the shaft 7. Whenever the shaft 7 is released and the power of the spring 16 applied thereto the gear 40 is turned by the gear 41 and the plate 37 turns a sheet-holder and the leaf held thereby and makes a complete rotation about the axis of the short shaft 38. A corresponding orbital movement 80 of the actuator proper 35 results from this rotation of the plate 37. At the beginning of operations the pin 35 is in the path of the projection 34 on the first sheet-holder of the series and strikes said projection and quickly 85 turns the first sheet-holder to the position shown in Fig. 1. In order that it may co-operate properly with the other sheet-holders, however, it is necessary that this actuator proper or pin 35 have an additional 90 movement so that it may move in arcs of different radii, and it is also necessary that the projections on the sheet-holders be located in different positions, that is, at different distances from the axis of the short 95 shaft 38.

In the construction shown there are six sheet-holders, and the projections therefrom are located in six different positions, as will be clear by reference to these projections, 100 which are indicated respectively by 34, 42, 43, 44, 45 and 46. Similarly the sheet-holders themselves are designated respectively 31, 47, 48, 49, 50 and 51. These projections on the sheet-holders are separated 105 from one another by intervals corresponding to the differences between the lengths of the radii of movement of the pin 35 at different operations. After turning the first sheet-holder 31 and its projection 34 to the position shown in Fig. 1 the actuator proper 35 should then be shifted out of the path of the projection 34 and into the path of the next projection 42. In order to accomplish this 110 we prefer to mount the actuator proper on a slide such as 36 and to provide means for moving this slide outward from the axis of the short shaft 38 one step after each operation of turning a sheet-holder. In order to accomplish this result the slide 36 is here shown as 115

having a toothed rack at one edge thereof with spur-teeth, designated by 52, which co-operate with teeth of a small pinion 53 mounted on the plate 37 near one edge thereof 5 of and in constant mesh with the teeth 52. The teeth of this pinion 53 are of such length that their path of movement passes through a co-operative fixed tooth 54 secured to the upper edge of the cross-bar 3. At each rotation 10 of the plate 37 and the actuator proper 35 this pinion moves in an orbit into engagement with the fixed tooth 54 which serves as a resistance actuator and turns the pinion 53 one step. This movement of the pinion 53 15 is imparted to the spur-teeth 52 of the co-operating rack at the edge of the slide 36, and said slide is moved outward one step, thus carrying the actuator proper 35 into position to swing on the next rotation of the 20 plate 37 into the path of the second projection 42, which is on the second sheet-holder 47 of the series. By successive operations this slide is moved out one step at a time to bring the actuator 35 successively into the 25 paths of the six projections 34, 42, 43, 44, 45 and 46. The slide is guided in its movements back and forth on the plate 37 in any suitable manner. It may also be shifted by hand when required to any desired position, 30 an upwardly-extending thumb-piece 55 the shank of which works in a slide 56 in the plate 37 serving the double function of providing a handle for shifting the slide back and forth and of guiding said slide at one 35 end of its movements. When all six sheet-holders have been turned by the device the slide should be drawn in to its original position by a pull on the thumb-piece 55. At the edge of the slide 36 opposite the rack-teeth 52 the slide is notched as shown at 57 with ratchet-teeth for engaging the end of a stop-pawl 58 on the under side of the plate 37, which stop-pawl serves to locate the slide 40 positively in each of its six positions and prevent under- or over-movement of the 45 same.

Our invention, though applicable to all uses of sheet-music, is especially adapted for pianos and organs. The frame of the instrument, as shown, has legs 59 depending therefrom which are finished by pads or cushions 60 of rubber or other suitable material. These are intended to rest on the polished woodwork of a piano. At its upper end the frame may have legs and feet similar to those shown at 59 and 60 for supporting it against an upright part of the piano or organ. The feet of these supports are indicated at 61.

For the purpose of releasing the spring 16 and permitting it to operate instantly upon the mechanism before described for turning the sheet-holders successively we prefer to employ a key located immediately over the 65 keys of the instrument, though other means

for releasing the spring may be used. The key for this purpose, which is similar to the keys of a typewriting machine, is shown at 62. By means of a connecting-rod 63 it is connected with a slide 64 mounted in this instance vertically on the frame of the apparatus near the bottom thereof, and slotted and guided on said frame in a manner well understood. This slide has a projection 65 which normally rests on the upper edge of 70 the escapement-lever 28. When the key 62 is depressed the projection 65 oscillates said lever and releases the dog 27 thereof from the dog 26 on the shaft 7, whereupon said shaft is instantly turned by the spring 16. 80 In the normal condition of the parts this shaft will turn in the direction to perform the principal operation hereinbefore described, that is to say, the turning of the first sheet-holder to the position illustrated in 85 Fig. 1. On the release of this key it is restored to its normal position by means of a spring 66, and the lever 28 is at the same time returned to its normal position by the spring 30 to bring its dog 27 back again into 90 the path of the co-operating dog 26. The slide 64 is here shown as also having a projecting arm 67 for the purpose of operating a shifting-lever 68 pivoted on a depending arm 69 of the framework and controlling the 95 movements of a coupling device for determining the direction in which the shaft 7 shall be turned when the dogs are released from engagement with each other. Normally this shifting-lever is in the position 100 shown in Fig. 1, with the upper bevel-gear 24 hereinbefore described of a train of bevel gears, coupled to the shaft 7.

When it is desired to reverse the direction of turn of the sheet-holders, that is to say, 105 when it is desired to turn back a sheet-holder, as for example, for repeating the music previously played, this may be accomplished by reversing the driving connections between the motor and the shaft 7 and releasing the 110 dogs 26 and 27 from engagement. For the purpose of accomplishing these results we make use of the mechanism illustrated, although various means may be employed for the purpose. 115

70, 71 and 72 designate a key, a connecting-rod and a slide similar to those shown at 62, 63 and 64. The slide 72 is also guided in the same manner as the slide 64 and has a similar spring 73 for returning it to its normal position. It also has at its inner edge a projection 74 normally engaging the upper edge of the escapement-lever 28 for operating the same when the key 70 is depressed, this 120 operation being exactly the same as that before described when the key 62 is depressed. The slide 72, however, is provided with means, such as a pin 75, for operating a short lever 76 suitably pivoted on the framework, the free end of which lies under one end of 125 130

the shifting-lever 68. When the key 70 is depressed the shifting-lever 68 is also operated, but is turned in a reverse direction to that in which it is turned by the projection 5 67 on the slide 64. When so operated by the key 70 a coupling device 25 controlled by the shifting-lever 68 is shifted from its upper position where it is normally in engagement with the upper bevel gear 24, to its lower 10 position into engagement with the lowermost bevel gear 78 of the train of bevel gears before mentioned. The intermediate gear of this train is designated by 79. This movement of the shifting-lever serves to reverse 15 the driving connection between the motor and the shaft 7 and to cause the rotation of the shaft 7 and all its coöperative parts in the opposite direction, thereby effecting the turning back of the sheet-holders and the 20 sheets carried thereby whenever it is desired to do so.

The two keys 62 and 70, it will be noticed, are placed close together in a convenient 25 position for operation, and by a slight movement either of them can be depressed to release the spring and thereby effect the quick turning of a sheet-holder in either direction desired.

Any suitable means may be employed for 30 winding the spring 16 whenever it is desired to do so. The means shown herein is a sliding rack coacting with the large pinion 22 mounted loosely on the spindle 14 of the spring motor. This rack is mounted on the 35 lowermost member 13 of the framework and is guided thereon by suitable pin-and-slot connections in the well known manner. Two such slots are indicated in Fig. 3 at 80 and 81. When the teeth of this rack, which is 40 designated generally by 82, are normally out of engagement with the teeth of the spur-pinion 22 as shown in these views one or both of the slots 80 and 81 be curved at one end, as shown, in order that when the 45 rack 82 is moved endwise it may be shifted at once into engagement with the teeth of the spur-pinion 22 and thus operate to turn said pinion and wind the spring. For the purpose of quickly effecting the re-winding 50 of the spring a rigid projecting thumb-piece 83 extends in this construction from the edge of the lowermost cross-bar 13, and a similar thumb-piece 84 extends from the edge of the rack 82. When the two are 55 engaged by the thumb and the forefinger, for example, the rack may be quickly forced to the right to turn the pinion 22 and wind the spring. A strong spring, such as 85, may be employed to return the rack to its 60 normal position after the spring 16 has been wound, this spring 85 serving to return the rack to said normal position as soon as the thumb-piece 84 is released.

What we claim is:

65 1. A music-sheet turner, comprising a

sheet-holder mounted to turn about an axis, a pivoted actuator associated with said sheet-holder for turning the same, a motor for imparting a quick turning movement to said actuator, connections between the motor and the actuator for changing the radius of throw of the latter, means for holding the motor inoperative and means under the control of an operator for releasing said holding means to permit operation of said motor. 75

2. A music-sheet turner, comprising a sheet-holder mounted to turn about an axis, a pivoted actuator associated with said sheet-holder for turning the same and mounted to turn about the same axis as said sheet-holder, a motor for imparting a quick turning movement to said actuator, connections between the motor and the actuator for changing the radius of throw of the latter, means for holding the motor inoperative and means under the control of an operator for releasing said holding means to permit operation of said motor. 80

3. A music-sheet turner, comprising a sheet-holder mounted to turn about an axis, a pivoted actuator associated with said sheet-holder for turning the same and mounted to turn about the same axis as said sheet-holder, a motor for imparting a quick turning movement to said actuator, connections between the motor and the actuator for changing the radius of throw of the latter, means for holding the motor inoperative, means under the control of an operator for releasing said holding means to permit operation of said motor, and means for limiting the turning movement of said actuator. 90

4. A music-sheet turner, comprising a plurality of sheet-holders separately oscillatory about a common axis, a pivoted actuator associated with said sheet-holders and coöperative therewith for turning them successively, a motor for imparting a quick turning movement to said actuator, connections between the motor and the actuator for changing the radius of throw of the latter, means for holding the motor inoperative, means under the control of an operator for releasing said holding means to permit successive operations of said motor, and means for limiting successive rotary movements of said actuator. 105

5. A music-sheet turner, comprising a plurality of sheet-holders separately oscillatory about a common axis, a pivoted actuator associated with said sheet-holders and mounted to turn about the same axis as said sheet-holders and coöperative with said sheet-holders for turning them successively, a motor for imparting a quick turning movement to said actuator, connections between the motor and the actuator for changing the radius of throw of the latter, means for holding the motor inoperative, means under the control of an operator for releasing said holding means to permit operation of said motor, and means for limiting successive rotary movements of said actuator. 115

the control of an operator for releasing said holding means to permit successive operations of said motor, and means for limiting successive rotary movements of said actuator.

5 6. A music-sheet turner, comprising a plurality of sheet-holders separately oscillatory about a common axis and each having a projection located at a different distance from said axis, a pivoted actuator associated 10 with said sheet-holders for coöperation with said projections successively, a motor for imparting a quick turning movement to said actuator, connections between the motor and the actuator for changing the radius of 15 throw of the latter at each operation and shifting it into position to coöperate with said projections successively, means for holding the motor inoperative, means under the control of an operator for releasing said 20 holding means to permit successive operations of said motor, and means for limiting successive movements of said actuator.

7. A music-sheet turner, comprising a plurality of sheet-holders separately oscillatory 25 about a common axis and each having a projection located at a different distance from said axis, a pivoted actuator mounted to turn about the same axis as said sheet-holders, a motor for imparting a quick turning movement 30 to said actuator, means controlled by said motor for bringing said actuator into operative relation with said projections successively as successive sheet-holders are operated, means for holding the motor inoperative, 35 means under the control of an operator for releasing said holding means to permit successive operations of said motor, and means for limiting successive movements of said actuator.

40 8. A music-sheet turner, comprising a plurality of sheet-holders separately oscillatory about a common axis and each having a projection located at a different distance from said axis, a pivoted actuator mounted to turn 45 about the same axis as said sheet-holders and also movable to positions at different distances from said axis, a motor for imparting a quick turning movement to said actuator, means controlled by the motor for 50 shifting said actuator to said different positions successively, means for holding the motor inoperative, means under the control of an operator for releasing said holding 55 means to permit successive operations of said motor, and means for limiting successive movements of said actuator.

9. A music-sheet turner, comprising a plurality of separately-movable sheet-holders oscillatory about a common axis and lying in 60 close contact with one another and each embodying a sheet-metal strip having at its pivot a quarter twist, a pivoted actuator associated with said sheet-holders for coöperation therewith successively, a motor for

imparting a quick turning movement to said 65 actuator, connections between the motor and the actuator for shifting the latter into position to coöperate with said sheet-holders successively, means for holding the motor inoperative, means under the control of an 70 operator for releasing said holding means to permit successive operations of said motor, and means for limiting successive movements of said actuator.

10. A music-sheet turner, comprising a 75 plurality of separately-movable sheet-holders each having a pair of clips one clip of each pair being adjustable along its holder, a pivoted actuator associated with said sheet-holders for coöperation therewith successively, a motor for imparting a quick turning movement to said actuator, connections between the motor and the actuator for shifting the latter into position to coöperate with said sheet-holders successively, means for 80 holding the motor inoperative, means under the control of an operator for releasing said holding means to permit successive operations of said motor, and means for limiting successive movements of said actuator. 90

11. A music-sheet turner, comprising a movable sheet-holder, an actuator having an orbital movement in a circuit about a point outside the actuator and associated with said sheet-holder for engaging and moving the 95 same, means under the control of an operator for governing the movement of said actuator in one direction, means also under the control of an operator for governing the movement of said actuator to move said sheet- 100 holder back to its original position, and a motor coöperative with said means for effecting said movements.

12. A music-sheet turner, comprising a plurality of sheet-holders separately oscillatory 105 about a common axis, a pivoted actuator having an orbital movement in a circuit outside its proof and associated with said sheet-holders and coöperative therewith successively for engaging the sheet-holders and 110 turning each of them in one direction, means under the control of an operator for governing the movement of said actuator in one direction, means also under the control of an operator for governing the movement of said 115 actuator to move each of said sheet-holders in the opposite direction, and a motor coöperative with said means for effecting said movements.

Signed at New York, in the county of 120 New York, and State of New York, this 6th day of May, A. D. 1907.
